C. L. ANDERSON

MERCHANDISE CABINET

Filed June 22, 1925

FIG. 1

FIG. 2

INVENTOR.
CLYDE L. ANDERSON
BY Joseph B. Gardner
ATTORNEY

UNITED STATES PATENT OFFICE.

CLYDE L. ANDERSON, OF OAKLAND, CALIFORNIA.

MERCHANTISE CABINET.

Application filed June 22, 1925. Serial No. 38,712.

My invention relates to merchandise sales cabinets, and particularly to cabinets provided with means for indicating the number of pieces of merchandise taken from or contained at any time in the different compartments thereof.

An object of the invention is to provide a cabinet of the type described in which an indication of the number of pieces or packages 10 of merchandise contained therein or removed therefrom is automatically mechanically indicated.

Another object of the invention is to provide a cabinet from which a record of the 15 number of packages removed therefrom during a given period of time may be directly obtained without recourse to written inventory records.

A further object of the invention is to provide a cabinet of the character described with merchandise recording means so arranged that the sizes of merchandise packages to be dispensed from a given compartment may be changed without effecting the accuracy of 25 record of the indicating means.

A still further object of the invention is to provide a cabinet of the character described in which the indicating mechanism is so arranged that unauthorized persons may be prevented from changing the indications 30 thereof.

Referring to said drawings:

Figure 1 is a front view of a cabinet embodying my invention, a portion of the front 35 thereof being broken away.

Figure 2 is an enlarged top view of a portion of the cabinet, with the top removed.

In the handling and sale of merchandise, more or less difficulty is experienced in determining the rate of "turnover" of the various 40 articles handled. The usual method of making such determinations has been by means of a written inventory, but such method has involved undue effort and inconvenience. In accordance with my invention, however, a 45 merchandise cabinet has been produced which might well be described as self-inventorying. Briefly expressed, the cabinet of my invention, and as here shown, comprises vertically disposed compartments in each of which the 50 different kinds of goods are placed in superposed relation, and from which they are ar-

ranged to be taken one at a time, preferably at the bottom. By means of an indicating mechanism automatically actuated by a member 55 arranged to maintain contact with the uppermost package in a compartment, the number of packages removed from the compartment is directly indicated at any time to give at a glance the desired information as to

the number of sales made since the setting of the indicator hand at zero. In this manner, a written inventory is avoided and a positive record is had at a glance. Since packages, 60

even in the case of successive receipts of the same kind of merchandise, may vary in size, means are provided for securing a true record by the use of the same dial, so that one dial 65 may serve for a wide range of sizes of packages. Furthermore, to protect and display 70

the goods and insure a correct record, the cabinet of my invention is preferably provided with a glass front which covers the recording mechanism as well as the merchandise, 75 openings only being provided at the removal points at the bottoms of the compartments, the glass front preferably being arranged to be locked in position. The cabinet of my invention, it will be noted, may be used equally well for both small and comparatively large 80 articles, the proportions only of the device being varied.

As illustrated, the device of my invention comprises a cabinet 4 in which are provided vertically disposed compartments A, B, C, D, 85 etc., arranged to respectively receive packages or pieces of merchandise A', B', C', D', etc., in superposed relation. Since the cabinet is arranged, among other things, to indicate the number of sales of the packages, the packages 90 in a given compartment desirably contain the same goods, both as to quality and number, and are therefore of the same shape. The packages are arranged to be removed one at a time from their respective piles, preferably at 95 the bottom. Since the packages are of uniform thickness, the removal of a package will lower the height of the corresponding pile by the amount of such thickness, and accordingly, a member 6 is provided which is arranged to rest on the uppermost package and move upwardly or downwardly therewith. 100 The various positions of the member 6, in accord with the number of packages thereunder

is arranged to be directly and automatically indicated by means of an indicator hand 7 arranged to be variously positioned in front of appropriate symbols on a dial 8 removably attached to a plate 9 fixed in the cabinet adjacent the top thereof.

Operative connection between the member 6 and a corresponding hand 7 may be variously accomplished, but since it may be desirable to use a given compartment for packages of different thickness, means are preferably provided whereby adjustment between the relative movements of the hand and member 6 may be accomplished to thereby allow the continued use of the same dial. As here shown, such means comprise a pulley wheel 12 and a cooperating friction wheel 13 arranged to bear against a side of the pulley, the latter being arranged to move the hand 7 and the former being arranged to be rotated upon movement of the member 6 by means of a flexible cord 14 wrapped therearound and secured at its other end to the member 6. The hand 7, it will now be noted, is secured to the end of a shaft 16 extending through and bearing in the plate 9 and a rear plate 17. As here shown, the shafts 16 extend horizontally in the direction of the depth of the cabinet and transversely and closely overlie a fixed shaft 18 horizontally disposed longitudinally of the cabinet. The pulleys 12, it will be noted, are revolvably mounted on the common shaft 18, while the wheels 13 are slidably mounted on the shafts 16 and are arranged to be set in position thereon by means of set screws 19 whereby their rotation will be directly communicated to the hands 7.

To insure proper frictional engagement of the discs and their corresponding pulleys, springs 21 are provided, such springs being here shown of helical form encircling the shaft 18 and secured at one end to the pulleys 12 and at the other end to collars 22 adjustably fixed to the shaft 18. In this manner, an operative frictional engagement between a wheel and its pulley may be readily maintained, while the cord 14 may be held taut at all times, the weight of the member 6 being such that the spring will at no time be able to lift it. Setting of the hand 7 in any desired position may be easily and quickly accomplished by manually moving the pulley 12 out of engagement with the wheel 13 against the resistance of the spring 21, so that the hand may thus be readily reset to zero at the close of a day's business or at any other time.

It will now be noted that the wheel 13 is arranged to be adjustably positioned so that it will contact with its pulley 12 at various radial distances on the surface thereof. In this manner, assuming the device to have been used for indicating the withdrawal of packages of a given size from a stock of 5, as shown in compartment A, if larger packages

are to be used with a similarly marked dial as shown in compartment B, it is merely necessary to position the disc 13 inwardly of its former position to insure a proper indication disclosing the number of larger packages in the compartment at any time. In this manner, close adjustment to the size of package is thus readily accomplished. If, as indicated in compartment C, the packages are small enough to allow an increased number to the compartment, a dial arranged to indicate a different total number may be used, and the dials are therefore preferably removably and exchangeably mounted on the plate 9.

A record of a previous reading of a dial or of the original contents of a compartment is arranged to be shown thereon by means of a hand 26 fixed to the dial and arranged to be manually set as desired. In order to prevent unauthorized manipulation of the indicating mechanism, the case is preferably provided with a front closure 27, formed either of a transparent or opaque material as may be desired and arranged to be locked in position, openings 28 being provided adjacent the bottom thereof to allow the removal or insertion of the packages. The portion 29 of the closure covering the indicating mechanism is preferably formed separate of the remaining portion of the closure and is preferably transparent.

I claim:

1. In a cabinet arranged to contain superposed packages, a movable member arranged to rest on the topmost package, a dial held fixed on said cabinet, an indicator hand, a pulley, a flexible member operatively connecting said pulley and movable member, and means including a friction wheel engaging a side of said pulley to cause the positioning of said hand opposite appropriate indicia on said dial to disclose the number of packages removed from said cabinet.

2. In a cabinet arranged to contain a plurality of superposed packages of like thickness, a movable member arranged to rest on the uppermost package, a dial, an indicator hand, means connecting said member and hand whereby said hand will be automatically positioned opposite a symbol on said dial to disclose the number of packages removed from said cabinet, and means arranged for the adjustment of said connecting means whereby true indications will be given by said hand on said dial for packages of various thickness.

3. In a cabinet arranged to contain a plurality of superposed packages of like thickness, a movable member arranged to rest on the uppermost package, a numbered dial fixed thereto, an indicator hand arranged to cooperate with said dial, a rotatable shaft carrying said dial, a friction wheel fixed on said shaft, a pulley arranged for rotation about an axis extending transversely of the

axis of said wheel and having a side thereof arranged to serve as a friction disc, means resiliently urging said side of said pulley against the periphery of said wheel, and means operatively connecting said pulley and said movable member whereby the number of packages removed from said cabinet may

be disclosed by the positioning of said hand with respect to the indicia on said dial.

In testimony whereof, I have hereunto set my hand at Oakland, California, this 13th day of June, 1925.

CLYDE L. ANDERSON.
